EJECTOR.

1,175,462.

Specification of Letters Patent. Patented Mar. 14, 1916.

Application filed May 6, 1914. Serial No. 886,719.

To all whom it may concern:

Be it known that I, MAURICE LEBLANC, a citizen of the Republic of France, residing at Val-sur-Seine, Croissy, Seine et Oise, France, have invented a new and useful Improvement in Ejectors, of which the following is a specification.

The present invention relates to ejectors for obtaining a high degree of compression and has for its object to construct a simple and efficient apparatus of this kind having perfect stability in operation and also capable of easy starting.

In order that the nature of the invention may be clearly understood it will be described with reference to the accompanying drawing in which—

Figure 1 is a sectional view of a simple form of ejector constructed in accordance with the present invention. Fig. 2 is a diagrammatic sectional view of a modified form of apparatus embodying my invention, and Fig. 3 is a sectional view along the line 3—3 of Fig. 2.

In ejectors of the kind to which the invention relates the motive fluid is conducted under pressure by one or more nozzles A into a chamber B into which flows from a pipe C the fluid or fluids to be entrained or ejected; the motive fluid draws these latter by friction into the converging-diverging diffuser D opening into a space E at pressure P. The pressure in the chamber B may be designated by p . The dimensions of the different parts of the ejector depend essen-

tially on the ratio $\frac{p}{P}$, and the amount of fluid which is to be passed through. It will be readily understood therefore that if an ejector is designed to obtain a high degree of compression in ordinary service its dimensions will not be suitable for starting or when the pressure p is varied.

At the moment of starting especially, the steam passing from the nozzles into the space at the pressure P has a speed which is very much less than when it passes out at the pressure p . On the other hand the density of the entrained fluid which is also at the pressure P and the mass ejected is much greater than it is under normal conditions, hence a larger mass of fluid flows into the diffuser at a lower speed. If the neck of the diffuser has been calculated for normal operation it will be too small for starting and this will take place with difficulty. If,

on the contrary, the neck is too large for normal operation the fluid column forced into the diffuser will have a contracted section which is smaller than the neck of the diffuser, it will therefore no longer exactly fit the sides of the diffuser and, starting from the moment when it separates itself from the sides, eddies will be formed which interfere with a good output and with the stability of the ejector. This objection would be avoided if the walls of the diffuser could be made elastic in such a manner as to enable them to mold themselves at all times to the fluid column. This result can be obtained by providing around the fluid mixture which is forced into the diffuser at the places where it tends to detach itself from the walls a fluid sheath which will act as an elastic wall and prevent the column from expanding and thus giving rise to eddies. For this purpose at the desired point in the neighborhood of the neck of the diffuser there is provided as shown on the drawing an annular nozzle which communicates with the space E at the pressure P, or with a space where this same pressure P is existing. At the moment of starting no fluid passes out of this nozzle but when a difference of pressure is produced between the upper part of the ejector and the outlet of the diffuser a corresponding difference of pressure arises between the outlet of the diffuser and the neck. The annular nozzle will then begin to discharge. The quantity of fluid passing into the neck of the diffuser increases with the difference of pressure and the nozzle is adjusted in such a manner that when normal conditions are attained the total quantity of fluid passing through the neck, namely motive fluid, ejected fluid and fluid discharged by the annular nozzle H, corresponds with the dimensions of the neck.

When the quantity of ejected fluid diminishes the pressure p tends to diminish, the pressure at the neck also diminishes, but the output of the annular nozzle increases so that the quantity of fluid passing through the neck is maintained constant. It will be seen that an ejector constructed in this manner has perfect stability, independent of the large ratio of the compression.

It may be observed that the quantity of fluid supplied to the diffuser by the annular nozzle can be very large without impeding the operation of the ejector in any way, be-

cause the speed of the fluid at the outlet of this nozzle is sufficient to compress it again to the pressure existing at the lower part of the ejector. The fluid discharged by the 5 annular nozzle may be air if the diffuser discharges into the atmosphere.

The annular nozzle may be replaced either by one or several distributing nozzles located along the length of the diffuser at 10 suitable points or by pipes of suitable form or by any other suitable arrangement.

In Figs. 2 and 3 I have illustrated an embodiment of my invention similar to the apparatus illustrated in Fig. 1, but in which 15 the annular nozzle H is replaced by an annular series of nozzles H' , the inlet ends of which are in communication with the region into which the ejector exhausts.

While I have illustrated but two embodiments of my invention, it will be apparent to those skilled in the art that various changes, substitutions, additions and omissions may be made in the apparatus illustrated without departing from the spirit and 25 scope of the invention as set forth by the appended claims.

What I claim is:

1. In an ejector, the combination of a nozzle for the motive fluid, an inlet for the 20 fluid to be exhausted, a converging-diverging diffuser and means for introducing into the diffuser fluid at a pressure equal to that of the ejected fluid.

2. In an ejector, the combination of a 25 nozzle for the motive fluid, an inlet for the fluid to be exhausted, a diffuser having a constricted portion and an admission port for auxiliary fluid adjacent said constricted portion of the diffuser.

3. In an ejector, the combination of a 30 nozzle for the motive fluid, an inlet for the fluid to be exhausted, a diffuser having a neck or constricted portion, and an admission port for auxiliary fluid between said nozzle and said neck.

4. In an ejector, the combination of a 35 nozzle for the motive fluid, an inlet for the fluid to be exhausted, a converging-diverging diffuser and a pipe connecting the space 40 into which the diffuser discharges with a port near the other end of said diffuser.

5. In an ejector, the combination of a 45 nozzle for the motive fluid, an inlet for the fluid to be exhausted, a diffuser having a neck or constricted portion and an annular port through which auxiliary fluid may be admitted to said diffuser between said nozzle and said neck.

6. In an ejector, the combination of a 50 nozzle for the motive fluid, an inlet for the fluid to be exhausted, a diffuser having a neck or constricted portion, an annular port 55 between said nozzle and said neck and a pipe

connecting said annular port to the space 60 into which the ejector discharges.

7. In an ejector, the combination of a nozzle for the motive fluid, an inlet for the fluid to be exhausted, a diffuser having a neck or constricted portion and a plurality 70 of nozzles through which auxiliary fluid may be admitted to said diffuser between said nozzle and said neck.

8. In an ejector, the combination of a nozzle for the motive fluid, an inlet for the fluid to be exhausted, a diffuser having a neck or constricted portion, a plurality of nozzles between said nozzle and said neck and a pipe 75 connecting said plurality of nozzles to the space into which the ejector discharges.

9. An apparatus of the character described comprising, a chamber having an inlet for the fluid to be exhausted, means for delivering impelling fluid to said chamber, a diffuser communicating with the chamber 85 and through which the impelling and the exhausted fluid (fluid-mixture) passes, and means for admitting, at the places where the fluid-mixture tends to detach itself from the wall of the diffuser, a fluid sheath which 90 will act as an elastic wall and prevent the column of fluid-mixture from expanding.

10. In an ejector, a convergent divergent tube having near one end an inlet for fluid to be exhausted, at least one divergent 95 nozzle for delivering impelling fluid to the inlet end of said tube, and a series of nozzles for delivering auxiliary fluid to the tube at points where the exhausted and impelling fluid (fluid mixture) traversing the tube tends to detach itself from the wall of the tube, whereby the auxiliary fluid 100 acts as an elastic sheath and prevents the fluid mixture from expanding.

11. In an ejector, a convergent divergent 105 tube having an inlet for the fluid to be exhausted communicating with the convergent portion thereof, at least one fluid delivery nozzle for delivering impelling fluid to the inlet end of said tube, and means communicating with the region into which said 110 ejector discharges for admitting auxiliary fluid from said region to said tube at the point within the tube where the exhausted and impelling fluid (fluid mixture) traversing the tube tends to detach itself from the wall thereof, whereby the auxiliary fluid acts as a filler for the tube and prevents the fluid mixture from expanding.

In testimony whereof I have hereunto subscribed my name this 21st day of April 1914.

MAURICE LEBLANC.
